O. J. & A. O. EVANS.
SAFETY SIGNAL.
APPLICATION FILED JAN. 9, 1917.

1,251,490.

Patented Jan. 1, 1918.

UNITED STATES PATENT OFFICE.

OWEN JAMES EVANS AND ATLEE OWEN EVANS, OF CANTON, OHIO.

SAFETY-SIGNAL.

1,251,490.

Specification of Letters Patent.

Patented Jan. 1, 1918.

Application filed January 9, 1917. Serial No. 141,425.

To all whom it may concern:

Be it known that we, OWEN J. EVANS and ATLEE O. EVANS, citizens of the United States, residing at Canton, in the county of Stark, State of Ohio, have invented a new and useful Safety-Signal, of which the following is a specification.

The present invention appertains to signals and semaphores, and aims to provide a novel and improved safety signal adapted especially for use upon automobiles for signaling the intentions of the operator to steer to the right or left or to stop, whereby to facilitate traffic and avoid confusion and collision.

It is the object of the invention to provide a safety signal of the nature indicated which is of novel and improved construction, which can be applied readily to various automobiles, and which will serve its office in a practical and efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a median section of the signal, portions being broken away and portions being shown in elevation.

Figs. 2 and 3 are sections taken on the respective section lines 2—2 and 3—3 of Fig. 1.

Fig. 4 is a plan view of the operating lever.

The device embodies a cylindrical casing 1 comprising the body 2 and inner and outer ends 3 and 4 attached in any suitable manner to the ends of the body, the ends 3 and 4 being preferably bulged outwardly or convexed. The casing 1 is preferably disposed at one side of the automobile in an outstanding horizontal position, suitable means being employed for supporting the casing. As illustrated, the inner end 3 of the casing has an outstanding bifurcated member 5 pivoted by a bolt 6 or otherwise to a horizontal arm

7 carried by a clamp 8 which can be applied to the wind shield or other suitable support of the automobile. The casing 1 is provided in its periphery or body 2 with opposite openings or windows 9 arranged at the front and rear, and said openings are preferably covered by panels 10 of glass or other transparent material.

Mounted for rotary movement within the casing 2 concentrically therein is a drum or signal member 11 composed of the disk 12 forming the inner end thereof, the ring or annulus 13 forming the outer end thereof, and panels 14, 15, 16 and 17 forming the octagonal periphery of the drum. The disk 12 and ring 13 are provided with marginal rabbets 18 of octangular form in which the panels 14 are seated, the ends of the panels abutting said disk and ring. There are two sets of panels, the corresponding panels of the two sets being diametrically opposite to one another. Each set includes a panel 14 bearing the legend "Right," the panel 15 colored green, a panel 16 bearing the legend "Left," and a panel 17 bearing the legend "Stop," the panels 14, 16 and 17 being suitably colored and either the letters or back ground thereof being transparent, the panel 15 also being transparent for the passage of light therethrough. The disk or plate 12 has a central boss 19 projecting toward the outer end of the casing, and oblique bolts 20 are inserted through suitable apertures in the ring 13 and their inner ends threadedly engage the boss 19, whereby when the bolts are tightened, the ring 13 will be drawn inwardly toward the disk 12, thus clamping the panels between the disk and ring, and rendering the signal drum rigid. The bolts 20 are in an oblique position and converge inwardly to the boss 19, so that said bolts will act as stays and braces.

In order to mount the signal drum for oscillatory movement within the casing, a supporting disk or plate 21 is fitted within the casing adjacent to the inner end thereof, and is provided with a central outwardly projecting bearing or pintle 22. The boss 19 of the drum has an outwardly projecting hub 23 mounted for rotation upon the bearing 22, and the outer end of the hub has a reentrant tubular portion 24 journaled through the bearing 22 and protrud-

ing inwardly past the plate 21. A pinion 25 is secured upon the protruding inner end of the portion 24 and bears against the plate 21 to hold the drum upon the bearing.

5 A lamp socket 26 is attached to the end of the hub 23, and an electric lamp 27 is carried by said lamp socket, it being noted that when the outer end 4 of the casing is removed, ready access is had to the lamp socket 26 through the ring 13. The conductors 28 of the lamp socket can extend through the tubular portion 24 of the inner end of the casing from which they can extend to the exterior. The lamp 27 is lighted during the 10 night time, to illuminate the interior of the drum and its panels.

As a means for oscillating the signal drum, a gear segment 29 is pivoted, as at 30, to the plate or partition 21 at the inner 20 side thereof, and its teeth mesh with the pinion 25. An arm 31 attached to the segment 29 has a flexible wire 32 attached thereto. This wire 32 is slidable through a flexible tubular casing 33 having one end attached to the inner end 3 of the casing 1 and having its other end attached to a segment 34 forming part of the controller. The segment 34 has a suitable clamp 35 applicable to the steering column or other suitable support 25 of the automobile within ready reach of the operator, and an operating lever 36 is pivoted to the segment 34 and the other end of the wire 32 is attached thereto. The segment 34 has suitable designations to assist 30 in the proper movement of the lever 36, and the segment can be notched to hold the lever 36 in its various positions. The segment 34 can also carry a switch 37 to control the circuit of the lamp 27, the lamp being extinguished during the day time, and being 40 lighted at night.

In operation, when the automobile is moving straight ahead, the lever 36 is moved to a position whereby to turn the drum 11 to 45 a normal position with the green panels 15 adjacent to the openings or windows 9, thus indicating to the traffic in front and rear that the automobile is moving, and giving a caution signal. It is evident that when the 50 lever 36 is moved, the wire 32 is reciprocated, whereby to oscillate the segment 29 which imparts movement to the pinion 25 and drum 11. When the operator intends to turn to the right, the lever 36 is moved correspondingly, to bring the panels 14 adjacent to the windows or openings 9, and when 55 the operator intends to steer toward the left, the drum 11 is turned to bring the panels 16 adjacent to the openings 9. Before 60 the automobile is stopped, the handle or lever 36 is moved to bring the "stop" panels 17 adjacent to the openings 9. The drum 11 having two sets of panels, will cause similar panels to register with the openings or windows 9 simultaneously, to provide signals

which are visible from both in front and in rear of the automobile.

Any suitable means, whether operated manually or mechanically, can be employed for turning the signal drum or member. 70

Having thus described the invention, what is claimed as new is:

1. A signal device embodying a drum composed of end members and panels disposed therebetween, and members connecting the 75 end members for drawing them toward one another to clamp the panels therebetween and to serve as stays and braces for the drum.

2. A signal device embodying a drum 80 composed of an end plate, an end ring and panels between said plate and ring, and members engaged through said ring and converging toward one another and engaging said plate to draw the ring toward the 85 plate.

3. A signal device embodying a supporting member having a bearing, a signal drum composed of a plate at one end, a ring at the other end and signal panels between said 90 plate and ring, said plate having a hub projecting toward said ring and journaled upon said bearing, a lamp carried by said hub within the drum, and members engaged through said ring and converging toward 95 one another and engaged with said plate to draw the ring toward the plate for clamping the panels therebetween.

4. A signal device embodying a supporting member having a bearing, a signal drum, 100 one end of which is provided with a hub projecting toward the other end, said hub being journaled upon said bearing and having a reentrant tubular portion extending through the bearing, and means connected 105 to said portion for holding the hub upon the bearing and for oscillating the drum.

5. A signal device embodying a supporting member having a bearing, a signal drum, one end of which is provided with a hub 110 projecting toward the other end and mounted for rotation upon said bearing, said hub having a reentrant tubular portion extending through said bearing, a lamp carried by said hub within the drum, conductors for the 115 lamp extending through said tubular portion, and means attached to said tubular portion for holding the hub upon the bearing and for oscillating the drum.

6. A signal device embodying a casing 120 having a window, a supporting plate within the casing having a bearing, a drum within the casing composed of a disk at one end, a ring at the other end and signal panels between said disk and ring, said disk having 125 a hub projecting toward the ring and journaled upon said bearing, members extending through said ring and engaged with said disk for clamping the panels between said disk and ring, the hub having a reentrant 130

tubular portion extending through said bearing, a lamp carried by the hub, conductors for the lamp extending through said tubular portion, and a member secured to said tubular portion and bearing against said plate for holding the hub upon the bearing and operable for oscillating the drum.

5 In testimony that we claim the foregoing

as our own, we have hereto affixed our signatures in the presence of two witnesses.
